(57) **CLAIM**

The ornamental design for an orthotic insert, as shown and described.

DESCRIPTION

FIG. 1 is a top perspective view of an orthotic insert, showing my new design.

FIG. 2 is a top plan view thereof.

FIG. 3 is a side elevational view thereof.

FIG. 4 is an opposite side elevational view thereof.

FIG. 5 is a front elevational view thereof.

FIG. 6 is a rear elevational view thereof; and,

FIG. 7 is a bottom plan view thereof.

The broken line foot and sandal portions in FIGS. 1 and 2 are included for the purpose of showing unclaimed environment only and form no part of the claimed design.

1 Claim, 4 Drawing Sheets
